VALVE

Fred W. McRae, Los Angeles, Calif., assignor to
Security Valve Co., Los Angeles, Calif., a co-
partnership

Application May 17, 1946, Serial No. 670,488

3 Claims. (Cl. 137—153)

1

This invention relates to improvements in valves of the check valve type designed to automatically and positively close when the pressure of fluid supplied to the valve falls below a predetermined degree.

Heretofore, valves of this general type have been devised wherein a diaphragm subjected to pressure within the valve housing actuates a latch to release the valve closure and allow the valve closure to seat whenever the pressure within the valve housing falls below the magnitude of pressure to which the valve has been adjusted to operate. In such constructions, however, the diaphragm has normally been disposed on the side of the valve housing and within a protective housing that limits its extreme movements. Such constructions have been unsuitable for use in valves conducting liquids in that the liquid may pass from the valve housing into the chamber of the diaphragm and to the extent to which it is trapped therein it interferes with the movement of the diaphragm. Consequently, in such constructions the valve is slow to operate when the pressure of the liquid has fallen below the desired amount.

An object of the present invention is to provide an improved valve of this type wherein the diaphragm is mounted on the top of the valve housing and while its movements are restricted to prevent rupture of the diaphragm the entrapment of liquid on one side of the diaphragm is avoided, thus enabling the valve to be used in lines conducting liquids and to be highly sensitive and quick in its operation.

Another object of the invention is to provide an improved diaphragm construction which is so designed as to avoid the necessity of puncturing the diaphragm in assembling parts therewith thus eliminating leakage through the diaphragm.

With the foregoing and other objects in view, which will be made manifest in the following detailed description and specifically pointed out in the appended claims, reference is had to the accompanying drawings for an illustrative embodiment of the invention, wherein:

Figure 1 is a longitudinal vertical section through the improved valve embodying the present invention; and

Fig. 2 is a view in end elevation of the valve shown in Fig. 1, parts being broken away and shown in vertical section.

Referring to the accompanying drawings wherein similar reference characters designate similar parts throughout, the improved valve comprises a valve housing 10 having an inlet 11 and an outlet 12. This valve housing is

2

adapted to be incorporated in a conduit or pipe line conducting liquids although its use is not restricted to liquids. Within the valve housing there is a seat 13 adapted to seat a valve closure 14 that is preferably pivotally mounted as at 15 on a closure carrier 16. The closure carrier is pivotally mounted by means of a transversely extending pintle 17 one end of which is preferably squared as indicated at 18 and normally covered by a cap 19. While the closure and closure carrier may swing downwardly under the influence of gravity to seat the closure on the seat 13 a spring 20 is preferably coiled around the pintle 17 and normally urges the closure carrier into closing position. The closure and closure carrier are normally maintained in fully open position by means of a latch 21 pivotally mounted at 22 within the housing and having a finger 23 engageable with the closure carrier 16. The latch is normally urged into a position wherein its finger engages the closure carrier 16 by means of a compression spring 24. The arm of the latch carries an adjusting screw 25 that can be adjusted upwardly or downwardly 25 and held in adjusted position by means of a jamb nut 26. The top of the housing is closed by a cap 27 retained on the housing such as by bolts 28 that extend through companion flanges on the cap and the housing 10. Between these companion flanges the edges of a diaphragm 29 are positioned. This diaphragm is preferably formed of a flexible material such as synthetic rubber and has positioned therebeneath a metal ring 30 in which there is a large central aperture surrounded by a downwardly bent portion 31. The portion 31 may be engaged by the diaphragm 29 to limit the downward movement of the diaphragm and prevent its becoming ruptured under extreme conditions. On opposite 30 sides of the diaphragm two metal plates 32 and 33 are provided which are preferably vulcanized directly to the diaphragm. The upper plate 32 carries a hollow stem 34 into which extends a guide stem 35 secured to a threaded plug 36. This plug is normally covered by a cap 37. A compression spring 38 is compressed between the plug 36 and the bottom of the stem 34 and normally urges the diaphragm downwardly against the pressure of the fluid admitted to the housing 10 through inlet 11. By adjusting the plug 36 the compression of the spring 38 may be varied. The guide stem 35 which slidably extends into the stem 34 serves to guide the movement of the diaphragm. 45 50 55 The operation of the valve is substantially as follows: When fluid such as liquid is supplied to the

housing 10 through the inlet 11 at the desired pressure this pressure is effective on the underside of the diaphragm to maintain it in approximately the position shown. However, if the pressure of the fluid falls below a predetermined degree the spring 38 is effective to force the diaphragm downwardly until the lower plate 33 engages the top of the adjusting screw 25. When the latch 21 is swung about its pivot 22 and against the action of the spring 24 the finger 23 will disengage the closure carrier 16 and allow the closure carrier and closure 14 to swing downwardly and seat on the seat 13, thus preventing further supply of the fluid to the outlet 12.

It will be noted that if the fluid supplied to the housing 10 is a liquid and enters the space between the diaphragm 29 and the downwardly bent portion 31 of the ring 30 that such fluid may readily escape through the large central aperture in the ring 31 and does not block or retard downward movement of the diaphragm when the pressure within the housing 10 falls.

The liquid that is thus escaping through the ring 30 also does not tend to tilt the diaphragm during such escape as liquid is descending over the inclined portion 31 equally on all sides. It will be noted further that as the plates 32 and 33 are vulcanized directly to opposite sides of the diaphragm that it is unnecessary to puncture the diaphragm in attaching the stem 34 thereto. Consequently, leakage through the diaphragm is avoided.

From the above-described construction it will be appreciated that the improved valve can be very easily and economically manufactured and assembled and may be advantageously employed in conduits conducting liquids wherein it is desired to shut off the liquid whenever the pressure has fallen below a predetermined degree. When the valve has once closed an intentional, manual, resetting of the valve is required to again open it. This is accomplished by removing the plug 19 and applying a key to the squared end 18 of the pintle 17 and swinging the closure carrier 16 upwardly against the action of spring 20 until the latch 21 is re-engaged.

Various changes may be made in the details of description without departing from the spirit and scope of the invention as defined by the appended claims.

I claim:

1. A valve comprising a body having an inlet and an outlet which are aligned with respect to each other, the outlet having a valve seat coaxially arranged with respect thereto, said body providing a lateral chamber above the valve seat, a valve closure pivotally mounted in the lateral chamber adapted to assume an open position wholly within the chamber and wholly out of the line of flow from the inlet to the outlet through the valve seat or assume a closed position against the valve seat, a latch pivotally mounted in the chamber engageable with the valve closure to hold the same in open position, a diaphragm in the top of the lateral chamber exposed on its lower side to the pressure in the body, and spring means between the diaphragm and the top of the chamber urging the diaphragm downwardly in opposition to the pressure to engage the latch and cause it to release the closure when the pressure in the body falls below a predetermined degree a coil spring engageable with the latch urging it into position

to engage the valve closure, there being an opening in the wall of the body into which the coil spring extends and a removable closure for said opening against which the coil spring is seated whereby on removal of the closure the latch may be caused to release the closure without the latch being engaged by the diaphragm.

2. A valve comprising a body having an inlet and an outlet which are aligned with respect to each other, the outlet having a valve seat coaxially arranged with respect thereto, said body providing a lateral chamber above the valve seat, a valve closure pivotally mounted in the lateral chamber adjacent one side thereof and near the valve seat adapted to assume an open position wholly within the chamber and wholly out of the line of flow from the inlet to the outlet through the valve seat or assume a closed position against the valve seat, a latch pivotally mounted on the opposite side of the lateral chamber engageable with the valve closure to hold the same in open position, a diaphragm in the top of the lateral chamber exposed on its under side to the pressure in the body, said latch having an arm extending over the valve closure in open position and carrying an adjusting screw arranged to be engageable by the under side of the diaphragm adjacent the center thereof, a compression spring disposed on the upper side of the diaphragm, an adjusting nut threadedly mounted in the top of the lateral chamber for adjusting the compression of the compression spring, and a plug removable from the top of the lateral chamber to provide access to the adjusting nut, the diaphragm being adaptable upon a decrease of pressure within the body to engage and actuate the latch and allow the closure to swing to its closed position.

3. A valve comprising a body having an inlet and an outlet which are aligned with respect to each other, the outlet having a valve seat coaxially arranged with respect thereto, said body providing a lateral chamber above the valve seat, a valve closure pivotally mounted in the lateral chamber adjacent one side thereof and near the valve seat adapted to assume an open position wholly within the chamber and wholly out of the line of flow from the inlet to the outlet through the valve seat or assume a closed position against the valve seat, a latch pivotally mounted on the opposite side of the lateral chamber engageable with the valve closure to hold the same in open position, spring means urging the latch into a position engaging the closure, there being an opening in the wall of the body into which the spring means extends and a removable closure in said opening on which the spring means is seated an arm on the latch extending over the closure, an adjusting screw on said arm, a diaphragm in the top of the lateral chamber exposed on its under side to pressure within the body, and adjustable spring means within the lateral chamber accessible from the exterior thereof for urging the diaphragm downwardly against the pressure to engage the adjusting screw on the arm and cause the latch to release the closure for closing movement when the pressure within the body falls below a predetermined degree.
